UNITED STATES PATENT OFFICE

OTTO BAUMGARTNER, OF WOLLINSEN, SWITZERLAND

VAPORIZER FOR INTERNAL COMBUSTION ENGINES

Application filed January 23, 1930, Serial No. 422,984, and in Switzerland December 16, 1929.

The subject of the present invention is an improvement relating to a vaporizer of hydrocarbons for internal combustion engines.

The vaporizer according to the present invention is of the kind operating without the usual nozzles and where the first mixture of air and fuel is obtained in passages branched off from the float chamber and communicating with lateral air inlets, the ends of which are fan-shaped and open into a second mixing chamber provided with a rotary sleeve-shaped valve member.

The particular feature of the present invention consists in that the converging passages for forming the first mixture open into a primary vaporizing chamber with which communicate, besides a controllable fuel passage provided with an additional air inlet, also two controllable air inlets, and only one single passage having a cell-shaped end leads the vaporized mixture into the second mixing chamber.

The annexed drawing represents one working example of the vaporizer according to the present invention, wherein

Fig. 1 is an end view of the vaporizer seen from the side of the actuating lever for the valve member,

Fig. 2 is a top view,

Fig. 3 is a vertical section on line III—III of Fig. 2 or on line III—III in Fig. 4 and

Fig. 4 is a vertical longitudinal section on line IV—IV in Fig. 3.

The vaporizer illustrated has a fuel chamber 1 with a float 2 fed through the neck 3 and the passage 4. This chamber communicates through a passage 5 with a primary vaporizing chamber 6 into which open from the above two air inlets 7 communicating with the atmospheric air through the windows 8. Said air inlets may be controlled by means of two lateral needle-screws 9. From said preliminary vaporizing chamber 6 one single vertical passage 10 ending into a cell-shaped slit 11 leads into the second mixing chamber 12 provided with a sleeve-like valve member 14 operated by means of an arm 13. By this device the free cross section of the slit 11 may be regulated. Also the fuel passage 5 is made adjustable by

means of a needle-screw 15 arranged at an acute angle with the passage 5. This needle-screw is hollow so that atmospheric air may be admitted to the fuel passage through a lateral outlet 16. A second controlling screw 17 of the fuel passage 10 is arranged at a right angle above the mixing chamber 6.

With a view of facilitating the manufacture and the inspection of this vaporizer the casing 18 is divided into two sections at 19 and the tight joint between the two sections is assured by means of two studs 20 which run across the lower section and are provided at their threaded ends with the nuts 21. By this contrivance the primary mixing chamber 6 and the two seats of the needle-screws 9 are made accessible to inspection.

The working of the vaporizer is as follows:

At the beginning of operations when the vaporizer is in its position of running idle the valve is very little open and fuel will be admitted through the passages 5, 10 controlled by the screws 15 and 17 and interrupted by the primary mixing or vaporizing chamber 6. At the same time the atmospheric air will flow through the windows 8 and the passages 7 into the chamber 6 and will counteract more or less depending on the adjustment of the screws 15, 17 the admission of the fuel. This fact will create eddies and cause a primary vaporizing. If the valve member 14 is now fully opened only fuel alone on account of its heavier weight than air and on account of the increased draught will get aspirated so that the chamber 6 will get filled with fuel and no more air will be admitted through the passages 7, but the fuel collected between the two screws 15, 17 will enter into the second chamber 12 and will enrich the mixture in this chamber and prevent any back-fires and the like. For the further operating of the engine that is in order to accelerate it steadily the screw 15 comes to work. This screw hinders the too fast admission of fuel and the air introduced by this screw will produce again a primary vaporizing of the fuel. By the peculiar arrangement of this vaporizer it will also be possible at full load of the engine and at slow speed to give full charge to the vapor-

izer without any risk of back-fires. This is proved beyond doubt by practical working and test and must be attributed to the tortuous path which the fire would have to travel and which is barred everywhere at least partly by the valve members.

What I claim as new is:

In a nozzleless vaporizer of hydrocarbons for internal combustion engines and in combination, a two-part casing, studs with nuts for joining said parts tightly, a float chamber and a first vaporizing and mixing chamber, both in the lower part of the casing, and a fuel passage connecting the two chambers, a needle-screw arranged at an acute angle to said fuel passage and adapted to control the same, and an axial air inlet in said screw having an opening into the fuel passage, two window-shaped air inlets in the upper part of the casing, and two air passages connecting the same to the first vaporizing chamber, needle-screws adapted to control said air passages, a second mixing and vaporizing chamber in the upper part of the casing, and a rotary sleeve-like valve member fitted into said second mixing chamber, and a fuel passage arranged between the two air passages and connecting the first with the second vaporizing chamber, and cell-shaped slits constituting the openings of said fuel passage into the second vaporizing chamber.

In testimony whereof I have affixed my signature.

OTTO BAUMGARTNER.
